Claims priority, application Great Britain, June 20, 1962, 23,783/62

7 Claims. (Cl. 253—39.15)

This invention relates to improvements in means for the discharge of liquid from rotors, and more particularly to water discharge means for the water cooled rotors of turbo-generators.

In a water cooled turbo-generator rotor, it is convenient to supply the cooling water to the rotor axially through one end of the rotor, for example as described in our copending patent application based on our United Kingdom Patent No. 971,507, applicants Associated Electrical Industries Limited, the cooling water then passing through passages or pipes in or on the rotor and being discharged from the rotor through radial or substantially radial ports in the rotor into a discharge chamber.

It is found that, due to the centrifugal pumping action of the rotating rotor upon the water contained in the radial ports in the rotor, low pressure zones are produced in the passages in the rotor and cavitation is liable to occur and give rise to erosion.

An object of the present invention is the provision of improved means for the discharge of liquid from rotors and of rotors provided with such improved means.

According to the present invention, means adapted to discharge liquid from a rotor comprise collecting chamber means in or on the rotor arranged to receive liquid to be discharged, ports extending outwardly from the chamber means and arranged when the rotor is stationary to discharge liquid from that chamber into a receiving chamber surrounding the rotor and arranged not to rotate with the rotor, and a venturi nozzle disposed in one of the said ports and through which the liquid flows, the throat of the venturi nozzle being provided with ports in communication with a source of gas, whereby when the rotor is rotating the gas is induced into the throat of the nozzle to reduce the density of the fluid flowing outwardly through the venturi nozzle and, when the speed of the rotor is sufficiently high to produce a sub-atmospheric pressure in the chamber means, to permit the outward flow of liquid through the venturi nozzle to cease and to permit the venturi nozzle to act as a gas inlet port to the collecting chamber means to reduce the degree of vacuum in the chamber means.

The invention will now be described, by way of example, with reference to the accompanying drawings, in which:

FIGURE 1 is a sectional side elevation through a short end part of a turbo-generator rotor shaft and an end part of an extension shaft secured coaxially thereto;

FIGURE 2 is a transverse sectional elevation taken on the line II—II of FIGURE 1;

FIGURE 3 is a sectional side elevation of a venturi nozzle shown in FIGURE 1 but drawn to a larger scale than in that figure; and

FIGURE 4 is a sectional plan view taken on the line IV—IV of FIGURE 2.

In FIGURE 1 the end of a turbine rotor shaft 1 has secured coaxially to it one end of a stainless steel extension shaft 3, the two shafts being formed with coaxial bores 5 and 7 respectively through which cooling water can flow in the direction indicated by the arrow 9. This water is utilised in passages and pipes in and on the turbo-generator rotor to effect cooling of the rotor, and the shaft 1 and the adjacent part of the extension shaft 3

2

are provided with an annular passage 15 through which cooling water can flow in the direction indicated by the arrows 19.

The extension shaft 3 is formed with an annular chamber 21 at which the annular passage 15 terminates, and from this chamber extend six radial ports 23 terminating at the periphery of the shaft 3, where they are aligned with holes 25 formed in an annular member 27 mounted on and rotating with the shaft 3. Member 27 is formed with cylindrical projections which are coaxial with the shaft 3 and are interleaved with similar projections on the inside of an annular chamber 29 which encircles the shaft 3 to form labyrinth seals. The lower end of the chamber 29 is provided with a drainpipe 31.

15 Two diametrically opposite ports 23 are each provided with a venturi nozzle 33. Each of these two ports 23 is screw-threaded throughout its length, and the nozzle 33 includes a main part 33A (see FIGURE 3) which is externally screw-threaded and screwed in place, and a 20 cap 33B having an internally screw-threaded annular skirt 35 by which the cap is mounted on a part of the main part 33A which lies inside the chamber 21. The main part 33A is formed with a bore of circular cross-section which diverges outwardly from the shaft axis. The cap 33B is formed with a bore of circular cross-section which diverges inwardly toward the shaft axis. The divergence of the bore in the cap 33B is greater than the divergence of the bore in the part 33A, and the two bores together 25 form an outwardly directed venturi nozzle. The outer surface of the part 33A is formed with four equally spaced, axially extending grooves 37 and at its inward end part 33A is formed with four radially extending grooves 39 which form extensions of the grooves 37. When the venturi nozzle is assembled in position as 30 shown in FIGURE 2, the grooves 37 and 39 together form passages which extend between the periphery of the shaft 3 and the throat of the venturi nozzle and through which air from outside the shaft 3 can be induced into the throat of the venturi nozzle.

35 When the rotor shafts 1 and 3 are stationary, and cooling water is pumped through the bores 7 and 5 and returning through the annular passage 15 to the chamber 21, the water flows from the chamber 21 outwardly through all six 40 of the ports 23 into the chamber 29 from whence it drains away through drainpipe 31. When the rotor shafts 1 and 3 are rotating, the cooling water continues to flow in the manner described above, but centrifugal force acting on the water in each of the ports 23 produces an outwardly 45 increasing pressure difference along the port. In the case of the four ports not provided with the venturi nozzles 33, this pressure difference increases with the speed of revolution of the rotor shaft, and could cause such a 50 reduced pressure in the chamber 21 that cavitation could occur in the chamber 21 and in the passages leading to it.

55 However, in each of the ports 23 provided with the venturi nozzle 33 a reduced pressure is produced at the throat of the venturi nozzle, and air from the chamber 60 29 flows through holes 25, along grooves 37 and through grooves 39 into the throat of the venturi nozzle. This air is entrained by the outflowing water. The density of the fluid passing through the divergent outer part of the nozzle is therefore less than if the nozzle were filled with water, 65 and as a result the pressure difference produced by the fluid in the nozzle is less. As the rotor speed increases still further, the increased suction in the chamber 21, in conjunction with the reduced pressure difference set up in the nozzle by the centrifugal force as the fluid density 70 decreases, causes the nozzle 33 to cease to discharge water and instead to act as an air inlet port for the flow of air

into the chamber 21 and so reduce the degree of vacuum in that chamber.

In this manner the danger of cavitation, and the consequent erosion of the passages in the rotor, can be reduced or avoided.

What I claim is:

1. A rotor provided with means adapted to discharge liquid from the rotor and comprising:

- (a) collecting chamber means arranged to rotate with the rotor;
- (b) liquid flow passages in the rotor arranged to discharge into the collecting chamber;
- (c) ports in the rotor and extending outwardly from the chamber means;
- (d) a stationary receiving chamber surrounding the part of the rotor provided with the ports and arranged to receive liquid discharged from these ports when the rotor is stationary;
- (e) means sealing the liquid in said receiving chamber and permitting air to enter into said chamber;
- (f) a venturi nozzle having a convergent inlet section and a divergent outlet section and a throat connecting these two parts, the nozzle being disposed in at least one of said ports and arranged for the through flow of the liquid when the rotor is stationary;
- (g) passage means in the rotor through which air can flow when the rotor is rotating at a sufficiently high speed to break the flow of liquid through the venturi nozzle so that the nozzle is able thereafter to act as an air inlet port for the radial inflow of air to the collecting chamber means, thereby to reduce the degree of vacuum in the said chamber means.

2. Liquid discharging means according to claim 1, in which the ports extend substantially radially outwardly from the collecting chamber means in the rotor.

3. Liquid discharging means according to claim 1, in which the collecting chamber means in the rotor are in the form of an annular chamber surrounding an inner chamber through which cooling liquid can flow on its way to cooling passages in the rotor before passing to the collecting chamber means.

4. Liquid discharging means according to claim 1, in which the venturi nozzle is formed in an elongated member fitted into a port provided in the rotor, and extending between the collecting chamber and the periphery of the rotor, and this elongated member is formed with at least one axially extending external groove opening to the atmosphere at the outer end of the member and opening

into the throat of the venturi nozzle towards the inner end of the member.

5. Liquid discharging means according to claim 4, in which the elongated member is externally screw-threaded, the port into which it is fitted is formed with a complementary screw thread, and the member includes a cap which has a skirt fitted onto the radially inner end of the screw threaded part, which is formed internally with one of the convergent parts of the venturi nozzle, and which when in place forms an axial boundary to a passage connecting the external groove to the throat of the venturi nozzle.

6. Liquid discharging means according to claim 1, in which a coaxial cylindrical projection carried by the rotor is interleaved between coaxial cylindrical projections on the receiving chamber to provide a labyrinth seal.

7. A liquid cooled turbine rotor provided with liquid discharging means comprising:

- (a) collecting chamber means arranged to rotate with the rotor;
- (b) liquid flow passages in the rotor arranged to discharge into the collecting chamber;
- (c) ports in the rotor and extending outwardly from the chamber means;
- (d) a stationary receiving chamber surrounding the part of the rotor provided with the ports and arranged to receive liquid discharged from these ports when the rotor is stationary;
- (e) means sealing the liquid in said receiving chamber and permitting air to enter into said chamber;
- (f) a venturi nozzle having a convergent inlet section and a divergent outlet section and a throat connecting these two parts, the nozzle being disposed in at least one of said ports and arranged for the through flow of the liquid when the rotor is stationary;
- (g) passage means in the rotor through which air can flow when the rotor is rotating at a sufficiently high speed to break the flow of liquid through the venturi nozzle so that the nozzle is able thereafter to act as an air inlet port for the radial inflow of air to the collecting chamber means, thereby to reduce the degree of vacuum in the said chamber means.
